BALL MILL

Ernest Saumenicht, Chatham, N. J.

Application January 11, 1943, Serial No. 471,951

3 Claims. (Cl. 241—70)

This invention relates to ball mills, and particularly to conical ball mills.

An object of the invention is to provide an improved conical ball mill that will have an increased output of material ground to a maximum fineness.

It is another object of the invention to provide an improved conical ball mill wherein the pulp is more readily discharged through the discharge throat of the mill.

It is a still further object to provide a conical ball mill that has particular merit in wet grinding in that the pulp level can be lowered substantially below the discharge throat of the mill and thereby increase the maximum efficiency of the mill.

It is another object of the invention to provide a ball mill that is adapted for either wet or dry grinding wherein the pulp is prevented from building up at the discharge throat by permitting removal of the pulp from the discharge throat at a level below the maximum normal height of the pulp in the discharge throat.

It is another object of the invention to provide a discharge throat for a conical ball mill that is constructed and arranged to lower the pulp level at the discharge throat to prevent the material from crowding at the discharge throat and thereby permit free discharge thereof to increase the capacity of the ball mill, the discharge throat being also constructed and arranged in a manner that the pulp that discharges through the discharge throat below the lowest point of the discharge opening is carried bodily around the discharge throat to permit its gravity discharge into a suitable carrier.

It is another object of the invention to provide a conical ball mill having means in the discharge throat for bodily lifting the pulp from the discharge throat and permitting the same to discharge therefrom by means of gravity.

A further object of this invention is to provide a conical ball mill having a discharge throat therein that is constructed and arranged in a manner that the pulp level is substantially lower than the normal overflow level at the discharge throat so that the massing of the pulp at the discharge throat is relieved when used for either dry or wet grinding; the lowering of the pulp level being accomplished without effecting the efficiency of the grinding operation in the ball mill and without altering the general conical shape of the discharge end of the ball mill to permit maximum grinding of the material to obtain maximum fineness of the material before it is discharged through the discharge throat.

Further objects and advantages will become apparent from the drawings and the following description.

In the drawings:

Fig. 1 is a side elevational view of a conical ball mill.

Fig. 2 is a longitudinal cross-sectional view of a conical ball mill having the improved discharge throat of this invention.

Fig. 3 is an enlarged end elevational view of the discharge grates in the discharge throat taken substantially along line 3—3 of Fig. 2.

Fig. 4 is an enlarged cross-sectional view taken along line 4—4 of Fig. 2.

Fig. 5 is a cross-sectional view of a portion of the improved discharge throat showing a slightly modified arrangement thereof.

Fig. 6 is a cross-sectional view of another modified arrangement of the discharge throat for the ball mill.

Fig. 7 is a transverse cross-sectional view of a discharge throat disclosed in Fig. 6 and is taken along line 7—7 of Fig. 6.

In this invention the ball mill 10 consists of a shell 11 that may be fabricated in any conventional manner. The shell 11 consists of a conical inlet end 12, a cylindrical portion 13 and a conical discharge end 14. The conical discharge end 14 is constructed so that the inner surface 30 of the shell forms an angle of approximately 30° with the axis of the mill 10. A liner 15 is provided within the shell 11 that may be constructed in sections to permit removal and replacement of any portion of the liner that should become worn or damaged. A trunnion 16 having an opening 17 therethrough is provided on the inlet end 12 of the shell 11, and a trunnion 27 is provided on the outlet or discharge end of the shell 11. These trunnions 16 and 27 are supported in suitable bearing members 18 and 19, respectively, whereby the shell 11 is rotatably mounted.

A gear 20 is secured to the shell 11 around the discharge end 14 thereof that engages a pinion 21 provided on an end of a drive shaft 22 extending from an electric motor 23. The pinion 21 and the gear 20 may be either of the spur or herring bone type. Also the direct drive connection from the electric motor 23 may be changed to a belt drive, or any other suitable mechanism for rotating the ball mill 10 can be provided.

The inlet opening 17 for the ball mill 10 has a feed chute 24 associated therewith for feeding material into the ball mill 10. The material discharged into the chute 24 may be controlled

in any suitable manner to regulate the quantity of the material that is fed into the ball mill and thus regulate the rate of discharge of the material from the ball mill. The ball mill 10 is provided with a discharge opening 25 provided in the cone-shaped end wall 14 of the shell 11 that has a discharge flange 26 associated therewith for discharging pulp into a suitable carrier.

The description of the ball mill just given is a general description of a conventional ball mill that is adapted for either wet or dry grinding. It is well-known that conical ball mills constructed and arranged in a manner disclosed in this application have the peculiar feature of segregating the balls in the mill so that the large balls are disposed within the largest diameter of the ball mill and as the diameter of the shell of the mill decreases toward the discharge opening that the balls automatically segregate themselves so that the size of the ball decreases toward the discharge opening. This arrangement provides an extremely efficient grinding mill wherein the largest particles are broken up by the largest balls and as the size of the granules of the material reduces as the material progresses through the ball mill, the smaller balls toward the discharge end of the mill break the material into fine particles. The fineness of the particle is, of course, determined by the size of the balls used, the period of time that the material is permitted to remain in the ball mill as well as the rate of feed of fresh material into the inlet end of the mill that causes a discharge of the material from the discharge end. The mill of this invention is adaptable for use for either open circuit grinding when all of the material is either a finished product or it is to be fed into subsequent mills for further grinding, or for closed circuit grinding wherein the material is to be discharged from the mill into a sizing device for grading the pulp and returning that portion of the pulp that is oversized. When used with dry grinding suitable air classifiers can be used to classify the material and return the oversized grains, or when used with wet grinding wherein water or other suitable liquid continuously flows through the mill to discharge the pulp therefrom, suitable grading apparatuses can be provided for classifying the size of the grains.

In the conventional type of ball mills the pulp has a tendency to mass or pack in the discharge throat of the ball mill because the material at this time has been reduced to the minimum granular size that is desired. This is particularly true in wet grinding because the wet material, or pulp, has a greater tendency to pack than dry material. When wet grinding in a ball mill it is desirable that the pulp level in the mill be maintained a predetermined distance above the lowest portion of the discharge throat, or at least substantially so, so that the pulp will be discharged from the mill in the same proportion as the fresh material is being added to the mill and thereby causing the ground material to overflow the discharge throat. In order to raise the pulp level to the point of overflowing the discharge throat which is the normal practice, the pulp has a tendency to crowd, or pack, at the discharge throat and thereby materially reduce the production capacity of the ball mill. The material moving through the discharge throat must therefore overcome this tendency to pack and as a result additional pressure is required to force the packed material upwardly along the cone-shaped wall of the discharge end of the mill,

whereby the finely ground material has a tendency to accumulate further back toward the center of the mill and thus reduce the operating efficiency of the mill.

In this invention there is provided an improved discharge throat for a ball mill that will permit discharge of the pulp from a lower level than would normally occur in the overflow type of discharge arrangement, and when the mill is used for wet grinding the level of the pulp can be just as low as when used for dry grinding.

The discharge throat 30 is provided with a plurality of triangular shaped grates 31 that are shaped arcuately transversely so that when a plurality of the grates 31 are disposed in engagement with one another that a cone-shaped grate member is provided. Each of the grates 31 are adapted to be independently secured within the discharge throat 30 of the ball mill and are spaced from the wall of the discharge end of the mill by means of flanges 32 provided along opposite edges of each of the grate sections 31, as shown in Fig. 4. A space 33 is thereby provided between each of the grates 31 and the wall 14 of the shell 11. The grates 31 have their large end in abutting engagement with the liner 15 and the face surface 34 of each of the grates 31 is in alignment with the face surface of the liner portion 15a adjacent the discharge end wall 14 of the ball mill 10 so that the surface of the grates 31 will be a continuation of the surface 15a and arranged upon the same angle as the surface 15a relative to the axis of the ball mill 10. With the surface of the grates 31 being a continuation of the surface 15a of the lining of the ball mill it is readily apparent that the forward motion of the pulp is not retarded any less in its travel upwardly along the surface of the liner 15a toward the discharge throat, or over the grates 31. Therefore, the efficiency of operation of the ball mill with the improved throat arrangement will not be effected by any increase in resistance to movement of the pulp toward the discharge throat.

Each of the grate sections 31 is provided with a plurality of openings 35 that are disposed over a major portion of the surface of the grate 31. However, there is a blank wall space 36 provided adjacent each of the flanges 32a so that pulp can be collected between the blank wall 36 and the flange 32a. A suitable liner 37 is provided between the grates 31 and the wall 14 of the shell 11 to prevent abrasion of the shell at the discharge opening. A screen 38 is provided over the apex end of the discharge throat 30 to prevent discharge of the balls from within the mill.

When the ball mill of this invention, with the improved discharge throat, is used for wet grinding, the material is fed into the ball mill 10 through the inlet or feed opening 17. The mill, of course, is rotated by means of the electric motor and the drive gear 20. Rotation of the mill produces the grinding action upon the material by means of the balls and the fine material is gradually advanced toward the discharge throat 30. The suitable liquid is continuously fed into the ball mill 10 through the inlet opening 17 so that there is a continuous admixture of liquid with the ground material to form the pulp that is discharged through the discharge opening 25. In the conventional conical ball mill of the overflow type the pulp level is being substantially at that level indicated in Fig. 2, so that there is a continuous overflow of pulp through the opening 25, the pulp level being

regulated by the lowermost edge of the opening 25 and the quantity of fluid and raw material that is being fed through the ball mill. Normally, in conventional ball mills the pulp must travel upwardly along the liner wall 15a until it reaches the lowermost edge of the opening 25 whereby the general forward motion of the pulp will carry it from the mill.

However, in this invention the pulp can be removed from the mill at a lower level than that established by the lowermost edge of the discharge opening 25.

In previous conical mills it was necessary to lower the position of the discharge opening and thus lower the general level of the pulp in the mill if a lower pulp level was to be obtained. This condition substantially reduced the output capacity of the conical mill because to reduce the general level of the pulp it was required that less material be fed through the mill.

In this invention, however, the openings 35 in the grates 31 permit the pulp to pass into the spaces 35 when they are disposed at a level beneath the discharge opening 25 so that the pulp will be removed from within the interior of the ball mill at a lower level than that normally established by the lowermost edge of the discharge opening 25. This permits relief of the crowding, or packing, of the pulp at the discharge throat, because it has a greater surface area of escape from the throat. It will be noted, however, that even though the pulp level is lowered in the mill, and can be lowered to the point indicated by the dotted line 41, that the general level of the pulp in the forward, or feeding end of the mill has not been lowered. Since the general level of the pulp has not been lowered the volume of the material capable of being handled in the mill is not reduced and the capacity thereof remains the same, and is actually increased because the pulp is removed from the discharge throat before there is any tendency of the pulp to pack at the discharge throat.

It is, of course, understood that the ball mill 10 is rotating during its operation, and as viewed from the right-hand end of the mill shown in Fig. 2, is rotating in a clockwise direction. Therefore, the pulp that discharges through the openings 35 in the grates 31 is picked up by the vanes 32a and carried upwardly bodily until the vanes pass over the horizontal center and begin to be disposed angularly relative to the horizontal as shown in the upper portion of Fig. 3. When the vanes 32a are in the position indicated by the vane 32aa, see Fig. 3, the pulp will slide forwardly on the vane over the blank wall surface 36 of the grate 31 and thus be discharged through the flange 26 adjacent the opening 25, this discharge, therefore, being by gravity flow.

When the ball mill is to be used for dry grinding the operation thereof will be identical with the operation just described.

In Fig. 5 there is shown a slightly modified form of the structure of the throat of the ball mill of this invention. It will be noted in Fig. 2 that the spaces 35 have been provided by increasing the thickness of the lining adjacent the wall 14 of the ball mill so that the surface of the grates 31 would be continuous with the surface of the lining 15a. In Fig. 5, however, the lining 45 is of the same thickness throughout the interior of the ball mill, or at least is the same thickness at the discharge throat 30. To provide a space to receive the vanes 32 of the grates 31,

an annular ring 46 is secured to the end of the wall 14 of the shell 11 whereby a space 35 is provided between the grates 31 and the annular ring 46, and the vanes 32 engage the annular ring 46 to support the grates 31 in the throat 30. The support trunnion 17a may be carried by the annular ring in place of being upon the shell wall 14, as heretofore described. The operation of the modified form of structure is identical as heretofore described regardless of whether a dry grinding or wet grinding operation is being performed.

In Figs. 6 and 7 there is shown a modified arrangement of a throat opening for a ball mill 15 wherein the pulp is picked up bodily from the lower portion of the mill and carried to the upper portion to be discharged by gravity in the same manner that the vanes 32a, heretofore described, pick up the pulp within the space 35 and carry it to the top of the mill so that it will be discharged by gravity. In the arrangement shown in Figs. 6 and 7, the lining and shell 50 of the discharge end of the conical mill is continuous to the discharge opening 51, a discharge flange 49 being positioned adjacent the discharge opening 51. A plurality of vanes 52 are positioned radially within the discharge throat 55 in engagement with the wall 50. A grate 53 is positioned adjacent the forward ends of the vanes 52 and is provided with a plurality of openings 54 through which pulp can pass through the discharge opening 51.

Since the vanes are secured to the wall 50 they will, of course, rotate when the ball mill rotates. The pulp passing through the openings 54 in the grate 53 will be caught by the vanes 52 and moved bodily upwardly until the vanes 52 have a downwardly inclined angle as indicated by the vane 52a, shown in Fig. 7, whereby the pulp will slide downwardly along the vane against the wall 50 to the discharge opening 51 and thereby be discharged from the ball mill by gravity flow.

It will be readily apparent that the vanes 52 will maintain a lower pulp level at the discharge throat 55 than if the pulp was permitted its normal flow through the ball mill until it was forced to overflow the lowermost edge of the opening 51, and this would be true whether the ball mill 15 was used for dry or wet grinding.

In the foregoing description it will become apparent that the pulp level in the ball mill can readily be controlled by the position of the innermost openings 35 in the grates 31, or by the innermost ends of the vanes 52. The position of these openings, or the ends of the vanes, is predetermined according to the size of granule that is to be discharged from the ball mill. Also, the position of the pulp level could be made readily adjustable by providing suitable means for closing certain of the rows of openings provided in the grates 31, or by controlling the position of the innermost ends of the vanes 52, all of which changes in pulp level at the discharge throat 65 can be controlled without reducing the general level of the pulp in the mill, or without reducing the discharge capacity of the mill regardless of whether it is used for wet or dry grinding. Also, the construction of the discharge throat in this invention reduces the horizontal travel of the pulp through the mill without reducing the efficiency of the grinding operation because the general level of the mass in the mill is above the pulp level at the discharge throat.

While the apparatus disclosed and described

herein constitutes a preferred form of the invention yet it is to be understood that the apparatus is capable of substantial alteration without departing from the spirit of the invention, and that all such modifications as fall within the scope of the appended claims are intended to be included herein.

Having thus fully described my invention, what I claim as new and desire to secure by Letters Patent is:

1. A discharge throat for a conical ball mill wherein the material being processed flows through the mill unidirectionally comprising a rotatable frusto-conical shell, an auxiliary frusto-conical shell of larger inner diameter than the inner diameter of the first shell connected to the apex of the first shell and forming a weir over which pulp can flow, a frusto-conical grate disposed within said auxiliary shell having the inner surface thereof substantially in alignment with the inner surface of the first shell and spaced from the auxiliary shell to form an annular space therebetween, openings in the periphery of said grate at least in the base portion thereof relatively to the apex of the grate to permit finish ground pulp to pass therethrough and enter said auxiliary shell below the apex thereof, and partition means extending between said grate means and said auxiliary shell to form means within the space therebetween to carry the pulp discharged into the same around the inner periphery of the auxiliary shell for discharge of the pulp through the apex of the auxiliary shell.

2. In a conical ball mill, a work chamber having a substantially frusto-conical discharge portion, a foraminous frusto-conical grate forming the apex of said discharge portion and not more than one-third thereof and having an axial discharge opening through which pulp from the work chamber may be discharged, a frusto-

conical discharge throat means adjacent said foraminous grate and spaced therefrom to form a chamber therebetween and having an opening through which pulp is discharged axially, the apex of said discharge throat being positioned adjacent the apex of said grate to control the minimum level of material in said work chamber, said foraminous grate extending radially below the radial level of said throat discharge opening whereby the pulp in the apex of said work chamber can pass through said foraminous grate into said chamber to lower the level of the pulp in the apex of the work chamber, and means for discharging the pulp from said chamber.

3. In a conical ball mill, a work chamber having a substantially frusto-conical discharge portion, a foraminous frusto-conical grate forming the apex of said discharge portion and not more than one-third thereof and positioned with the inner surface thereof in alignment with the inner surface of said discharge portion to form a continuation thereof and provided with an axial discharge opening for pulp from said work chamber, frusto-conical means forming a chamber adjacent said foraminous grate with the apex edge thereof forming a barrier to maintain a minimum material level in said work chamber and over which pulp from the work chamber flows, said foraminous grate permitting pulp in the apex of said discharge portion to enter the last mentioned chamber at a level below the overflow edge of said barrier to thereby lower the pulp level in the apex of the discharge portion below that which would normally be maintained by said barrier, and means in said last mentioned chamber for moving pulp therefrom to above the level of said barrier and permit the pulp to discharge therethrough.

ERNEST SAUMENICHT.
